UNITED STATES PATENT OFFICE.

DELMAR A. WHITSON, OF LOS ANGELES, CALIFORNIA, ASSIGNOR TO STENTORPHONE COMPANY, OF LOS ANGELES, CALIFORNIA, A CORPORATION OF CALIFORNIA.

JUNIOR LOUD SPEAKER.

Application filed November 20, 1923. Serial No. 675,804.

To all whom it may concern:

Be it known that I, DELMAR A. WHITSON, a citizen of the United States, residing at Los Angeles, in the county of Los Angeles and State of California, have invented a new and useful Junior Loud Speaker, of which the following is a specification.

This invention relates to loud speakers of the type commonly employed with radio receiving sets, whereby a tone of sufficient magnitude to be heard throughout a fairly large sized room is produced.

In such devices it is common practice to employ a diaphragm and means for vibrating the diaphragm, which vibrating means is actuated through a fluctuating audio current. Such vibrating means generally takes the form of the permanent magnet through which magnetic field it is produced, this magnetic field having an armature therein which is polarized by a fluctuating magnetic field produced by coils surrounding the armature, these coils being energized through an exciting circuit. A great many elements or conditions enter into the efficient operation of such devices. It is often found that where a device is designed and proportioned to operate on a certain strength of current with a fair degree of perfection, such a device is inoperative on either a higher or lower voltage circuit.

It is an object of this invention to provide a loud speaker which will operate over a wide voltage range.

An element entering into the efficiency of a loud talker of this character is the manner of mounting or supporting the armature. Certain devices now in use which operate very successfully on low value currents employ delicate wires for supporting the armature and depend principally upon the stiffness of the diaphragm for restoration of the armature after each vibratory movement due to magnetic action. It is found that

although this device operates very successfully on a low voltage current, when the voltage is raised, the tone quality is lost, and distortion of tone values to the effect of producing a marked clatter results. In

other types of devices the armature is supported upon a torsion plate which twists under the movement of the diaphragm, the

torsion of the plate serving as a restorative force for returning the armature after movement due to magnetic forces. 55

The high quality of tonal effects produced by my device may be credited principally to the improved form of mounting employed for support of the armature. This mounting consists of a plate having an edge to which the central portion of the armature is rigidly secured in such a manner that the movement of the armature produces a compound flexure in a designated portion of the plate, this compound flexure consisting of a composition of cantilever and beam flexures which, judging from the effects produced by the use thereof, results in an evenly graduated restorative means which approaches perfection in the design to the effect that high tone quality is obtainable over a wide range of energy input, thus suiting the device for use with various types to radio receiving equipment. 65 70

An object of the invention is to provide simplified forms of construction for the various parts of the device whereby the loud speaker may be produced and marketed at a comparatively low price. 75

It is a further object of the invention to provide means for adjusting the pole fixtures between the poles of the magnet, this adjustment being possible after assembly of the various motivating parts; and to provide means for adjusting the armature between the poles of the pole fixtures, thus enabling the adjustment of the armature in such a manner that liability of freezing up is reduced to a minimum and enabling the finding of the point of greatest sensitivity. 85 90

The especial advantages of the invention and further objects thereof will be made evident hereinafter.

Referring to the drawings which are for illustrative purposes only,

Fig. 1 is a horizontal section through a loud speaker embodying the features of my invention.

Fig. 2 is a section taken on a plane represented by the line 2—2 of Fig. 1. 100

Fig. 3 is an enlarged fragmentary section as indicated by the line 3—3 of Fig. 1.

Fig. 4 is a fragmentary section taken on

a plane represented by the line 4—4 of Fig. 3 showing the pole piece fixture and the field and the field coils in place therein.

Fig. 5 is an enlarged perspective view of a pole piece fixture.

Fig. 6 is an enlarged sectional perspective view taken on a plane indicated by the line 6—6 of Fig. 4 and showing the construction of the mounting plate and the manner in 10 which the armature is secured thereto.

Fig. 7 is an enlarged fragmentary section showing the novel means employed for securing the primary and secondary plates together.

Fig. 8 shows the manner in which leads are connected into the device.

Fig. 9 is a perspective view of the magnet clamping yoke.

Fig. 10 is a diagram illustrating the action produced in the device.

As shown principally in Fig. 1 of the drawing, a circular stamped primary plate 15 is formed with a central opening defined by an outward projecting lip 16, in 15 which is secured a threaded cup-shaped member 17 having the bottom 18 thereof perforated as indicated at 19. The member 15 is stepped so as to provide an annular edgewards disposed ledge 21, against which the circular edge of a diaphragm 22 is placed. The edge of the diaphragm 22 is gripped by a ring 23 preferably of rubber or other resilient material, this ring being forced against the ledge 21 by a secondary 25 plate 24 which is dish-shaped as indicated at 25 and is provided with an upwardly turned lip 26. The manner in which the plate 24 is secured in place is of marked 30 simplicity and novelty, consisting of three clips 28 spaced at angles of substantially 120 degrees, these clips having the outer ends 29 thereof turned downwardly, as indicated in Fig. 7. The central portions 30 of the clips 28 rest on the annular corner 31 35 of the secondary plate 24 and serve as levers for forcing the plate 24 inwardly. This leverage action is accomplished as follows:

The downwardly turned end 29 of each 50 clip 28 engages the interior of the inwardly rolled semi-circular lip 33 of the primary plate 15. When screws 34, which thread into holes provided in the member 24 and which extend through holes in the inner 55 ends of the clips 28, are tightened down the ends 29 react against the inner faces of the lips 33 in the direction indicated by the arrow 35, thus causing pressure to be applied at the corners 31 by the central portion 60 of the clip in such a manner that the plate 24 is forced tightly against the ring 23. This method of securing is very rigid and is accomplished without screws or other securing means showing upon the face of the primary plate 15.

The secondary plate 24 serves as a mount-

ing for a permanent horseshoe or U-shaped magnet 37, which is secured thereto by a special form of yoke 38 of the design shown in Fig. 9. This yoke has a central base portion 39, from the ends of which there 70 outwardly extend legs 40 having laterally projecting ends 41. From one side of the base portion 39 there upwardly extends a leg 42, which segregates into a center post 43 having a laterally extending end 44 75 provided with a threaded hole 45, and binding post supports 46 and 47 which are in the form of tongues having holes 48 drilled in the ends thereof. As shown in Figs. 1 and 2, the legs 40 of the yoke rest snugly 80 within the poles 49 and 50 of the magnet 37 and the ends 41 engage the outer faces of the poles with sufficient pressure to hold the magnet tightly against the member 24 when the screws 52 are screwed tightly 85 down. A semi-circular notch 53 is formed in the base portion 39 so that the central opening 54 of the member 24 will not be obstructed.

Secured on the inner face of each pole 49 and 50 is a fixture 56 formed from mild steel or iron in the manner shown in Fig. 5. These fixtures 56 are counterparts and when in use are placed in inverted positions, as shown clearly in Fig. 3. The fixture 56 95 comprises a base or attachment portion 57, from which there outwardly extends from opposing edges 59 a pair of legs 58. From one transverse edge 60 of the base portion 57 there is outwardly bent a web portion 62 100 which extends between the inner faces of the legs 58, and projecting from the other transverse edge 63 is a lug 64 turned so as to lie in a plane parallel with the legs 58 and having a threaded hole 65 therein. The legs 58 are offset in the manner shown at 105 67 so that the pole faces 68 thereof lie in a plane intermediate the edges 60 and 63, which plane is perpendicular to the plane of the inner faces of the legs 58.

As shown in Fig. 3, the fixtures 56 are placed in inverted position so that the pole faces 68 of one fixture will lie adjacent and parallel to the pole faces of the other fixtures, the fixtures being held in place by screws 70 which extend through the magnet poles 49 and 50 and thread into the base portion 57 of the fixtures 56. The fixtures as shown are turned sideways with respect to the poles so that the faces 68 thereof will lie parallel to a plane designated by the line 4—4 of Fig. 3, which plane when the magnet is secured to the secondary plate 24 is parallel to the surface of the plate 24. When the fixtures 56 are placed in this manner, the lugs 64 lie substantially in a central plane 115 and serve as securing points for an armature mounting plate 73.

The armature mounting plate should receive especial consideration as therein lies a 120 125 130

principal feature of the device and constitutes a part which is particularly important to the efficient operation thereof. This plate as shown in Figs. 3, 4 and 6 is preferably of 5 rectangular form with diagonally extending ears 74 having holes 75 therein. The mounting plate is preferably stamped from bronze and has a continuous oblong channel 76 depressed therein, which channel has a rigid 10 frame for the central flexure portion 77 of the mounting plate which has an elongated rectangular opening 78 therein through which an armature 79 extends, this armature preferably consisting of a flat bar of soft 15 iron and having a lever arm 81 extending from one end thereof. Although, it is convenient to confine a central flexure portion 77 of the plate by a frame composed of a depressed channel 76, it will be recognized that 20 other frame means may be employed to rigidly support the flexure portion 77. The armature 79 is secured rigidly to the upper edge 83 presented by the flexure portion, this being accomplished by the use of a 25 U-shaped wire member 84, the legs 85 of which extend through holes in the armature and rest against the face of the flexure portion 77, silver solder being flowed into the corner between the armature 79 and over the 30 legs 85, thus rigidly securing the armature to the flexure section 77 in such a manner that any movement of the ends of the armature will result in a compound flexure in the portion 77. This compound flexure consists 35 of a cantilever flexure, of that portion 77 of the plate to which the armature is secured, along the line A—A and a beam flexure along the line B—B. The reason that the restorative action of this compound flexure 40 of the supporting plate should be more efficient than a torsional restoration as accomplished by Edgerton or a simple flexure as attained by Baldwin, is not theoretically accounted for; but numerous experiments 45 definitely prove that the construction herein described is essential in the attainment of the efficient results, and in comparative tests, the quality and magnitude of tone delivered is plainly superior to the results attained in 50 the use of the devices now on the market. It is found also that the enclosing of the central flexure area by a frame for maintaining the peripheral edges of the area rigid contributes to the results attained. 55 The mounting plate 73 is disposed intermediately between the legs 58 of the fixtures 60 as shown, and is supported by screws 87 which extend through the openings 75 and thread into the lugs 64. The openings 75 are of larger diameter than the screws 87, thus allowing a relative movement of the plate so that the armature may be readily centralized between the pole faces of the 65 legs 58 as shown in Figs. 1 and 3. The projection 81 of the armature 79 extends in- wardly between the poles 49 and 50 of the permanent magnet and the movement thereof is linked with the diaphragm 22 by a small rod 90 which extends through the opening 54 in the mounting plate 24. It will 70 be noticed that the lugs 64 project slightly beyond the side faces of the permanent magnet 37 and that when the magnet is secured against the plate 24, the uppermost lug 64 is received in an opening 91 stamped in the 75 plate 24 as shown in Fig. 1.

A simplified form of exciting coil construction is employed in the device, this construction consisting of a pair of rectangular end plates 94 between which the winding is 80 held. This construction employs no interior sleeve for supporting the winding and the end plates 94, the coil being wound between the plates 94 on a mandrel of rectangular section, the winding being impregnated with liquid celluloid so that the separate turns of the wire are cemented together and to the inner faces of the plates 94. The coils 92 are of such rectangular form that they fit snugly between the base 85 portions 57 of the fixtures 56 when these fixtures are secured between the poles 49 and 50 of the permanent magnet, the openings through the coils formed by the mandrel 90 upon which they are wound, providing ample clearance for the armature to swing 95 therein. The form of pole fixtures employed in this device provides a boxed-in space which receives the coils, thus forming a very compact and easily assembled mechanism. 100

Means for connecting into the energizing circuit are provided in the form of pins 95 which extend through bushings 96 set in the openings 48 of the tongue members 47 stamped on the yoke 39. This pin is threaded at one end so as to receive a nut 97 and has an eye 98 in the opposite end thereof. The leads 100 and 101 from the coils 92 are soldered to the end of the pin 95 as shown. The external conductors are led through an 105 opening 102 in the cup shaped cover 103, and the ends thereof inserted through the eyes 98, whereupon the nuts 97 are tightened so as to draw the pin inwardly through the bushing in a manner to grip the conductors 110 tightly. This simple form of connection eliminates considerable time in the assembly 115 of the device and the parts thereof are inexpensive. The cup member 103 which serves as a cover for the mechanism is secured by a single screw 105, Fig. 1, which threads into the threaded hole 45 of the mounting post 43. The rim 110 of the cup rests within the lip 33 of the primary plate 15 and against the clips 28 as shown. This construction provides an easy access to the 120 interior mechanism and enables the device to be accurately adjusted before placing on the cover. 125

I claim as my invention: 130

1. In a loud speaker, the combination of means for producing a pair of uni-directional parallel magnetic fields; an armature extending between said magnetic fields and with the ends thereof in said magnetic fields; means for polarizing said armature; a diaphragm; means for transmitting the movement of said armature to said diaphragm; and a supporting plate having a flexure area confined by a frame structure, said armature being attached rigidly to the edge of said plate in such a manner that the movement of said armature is resisted by compound flexure in said plate.
2. In a loud speaker, the combination of means for producing a pair of uni-directional parallel magnetic fields; an armature extending between said magnetic fields and with the ends thereof in said magnetic fields; means for polarizing said armature; a diaphragm; means for transmitting the movement of said armature to said diaphragm; and a supporting plate, said plate having a flexure area confined by a frame structure, and said armature being attached rigidly to the edge of said plate in such a manner that the movement of said armature is resisted by compound flexure in the flexure area of said plate.
3. In a loud speaker, the combination of: means for producing a pair of uni-directional parallel magnetic fields; an armature extending between said magnetic fields and with the ends thereof in said magnetic fields; means for polarizing said armature; a diaphragm; means for transmitting the movement of said armature to said diaphragm; and a supporting plate, said plate having a centrally disposed flexure area confined by a frame structure and provided with an elongated opening through which said armature extends, said armature being rigidly secured to one longitudinal edge of said opening so that the movement of said armature is resisted by compound flexure in the flexure area of said plate.
4. In a loud speaker, the combination of: means for producing a pair of uni-directional parallel magnetic fields; an armature extending between said magnetic fields and with the ends thereof in said magnetic fields; means for polarizing said armature; a diaphragm; means for transmitting the movement of said armature to said diaphragm; and a supporting plate, said plate having a centrally disposed flexure area confined by a frame structure and provided with an elongated opening through which said armature extends, said armature being rigidly secured to one longitudinal edge of said opening so that the movement of said armature is resisted by compound flexure in the flexure area of said plate.
5. In a loud speaker, the combination of: means for producing a pair of uni-directional parallel magnetic fields; an armature extending between said magnetic fields and with the ends thereof in said magnetic fields; means for polarizing said armature; a diaphragm; means for transmitting the movement of said armature to said diaphragm; and a supporting plate having a centrally disposed flexure area confined by a frame structure consisting of a continuous channel depressed in said plate and provided with an elongated opening through which said armature extends, said armature being rigidly secured to one longitudinal edge of said opening so that the movement of said armature is resisted by compound flexure in the flexure area of said plate.
6. In a loud speaker, the combination of: means for producing a pair of uni-directional parallel magnetic fields; an armature extending between said magnetic fields and with the ends thereof in said magnetic fields; coils surrounding said armature for creating an excited field polarizing said armature; circuit leads to said coils; a diaphragm; means for transmitting the movement of said armature to said diaphragm; and a supporting plate having a flexure area confined by a frame structure, said armature being attached rigidly to an edge of the flexure area of said plate in such a manner that the movement of said armature is resisted by compound flexure in said plate.
7. In a loud speaker, the combination of: means for producing a pair of uni-directional parallel magnetic fields; an armature extending between said magnetic fields and with the ends thereof in said magnetic fields; coils surrounding said armature for creating an excited field polarizing said armature; circuit leads to said coils; a diaphragm; means for transmitting the movement of said armature to said diaphragm; and a supporting plate disposed centrally with respect to the ends of said armature, said plate having a centrally disposed flexure area confined by a frame structure consisting of a continuous channel depressed in said plate and provided with an elongated opening through which said armature extends, said armature being rigidly secured to one longitudinal edge of said opening so that the movement of said armature is resisted by compound flexure in the flexure area of said plate.
8. In a loud speaker, the combination of: a permanent U-shaped magnet; a pair of fixtures on said magnet for dividing the flow of magnetic flux into a pair of uni-directional parallel magnetic fields; an armature extending between said magnetic fields and with the ends thereof in said magnetic fields; means for polarizing said armature; a diaphragm; means for transmitting the movement of said armature to said diaphragm.

- phragm; and a supporting plate disposed centrally with respect to the ends of said armature, and having a flexure area confined by a frame structure, said armature being attached rigidly to an edge of the flexure area of said plate in such a manner that the movement of said armature is resisted by compound flexure in said plate.
9. In a loud speaker, the combination of: a permanent U-shaped magnet; a pair of fixtures on said magnet for dividing the flow of magnetic flux into a pair of uni-directional parallel magnetic fields; an armature extending between said magnetic fields and with the ends thereof in said magnetic fields; coils surrounding said armature for creating an excited field polarizing said armature; circuit leads to said coils; a diaphragm; means for transmitting the movement of said armature to said diaphragm; and a supporting plate disposed centrally with respect to the ends of said armature, said plate having a centrally disposed flexure area confined by a frame structure consisting of a continuous channel depressed in said plate and provided with an elongated opening through which said armature extends, said armature being rigidly secured to one longitudinal edge of said opening so that the movement of said armature is resisted by compound flexure in the flexure area of said plate.
10. In a loud speaker, the combination of: a permanent U-shaped magnet; a fixture on each arm of said magnet, each of said fixtures having a pair of parallel arms, the arms of each fixture extending in position spaced apart from the arms of the other fixture in a manner to divide the flow of flux of said magnet in a pair of uni-directional fields; an armature having the respective ends thereof in said fields; a plate for supporting said armature, said plate having a flexure area confined by a frame structure and having an opening therein through which said armature extends; and means for adjustably securing said plate in such a manner that said armature may be adjusted in position relative to said fixture arms by movement of said plate.
11. In a loud speaker, the combination of: a permanent U-shaped magnet; a fixture on each arm of said magnet, each of said fixtures having a pair of parallel arms, the arms of each fixture extending in position spaced apart from the arms of the other fixture in a manner to divide the flow of flux of said magnet in a pair of uni-directional fields; an armature having the respective ends thereof in said fields; a plate for supporting said armature, said plate having a flexure area confined by a frame structure and having an opening therein through which said armature extends; and lugs on said fixtures to which said plate is adjustably secured in such a manner that said armature may be adjusted in position relative to said fixture arms.
12. In a loud speaker, the combination of: a permanent U-shaped magnet; a fixture on each arm of said magnet, each of said fixtures consisting of a base portion having a pair of arms extending outwardly from one side thereof; the arms of each fixture overlapping the arms of the other fixture in spaced relationship in a manner to divide the flow of flux of said magnet in a pair of uni-directional fields; an armature having the respective ends thereof in said fields; a plate for supporting said armature said plate having a flexure area confined by a frame structure and having an opening in said flexure area through which said armature extends; and means for adjustably securing said plate in such a manner that said armature may be adjusted in position relative to said fixture arms by movement of said plate.
13. In a loud speaker, the combination of: a permanent U-shaped magnet; a fixture on each arm of said magnet, each of said fixtures consisting of a base portion having a pair of arms extending outwardly from one side thereof; the arms of each fixture overlapping the arms of the other fixture in spaced relationship having a pair of parallel arms, the arms of each fixture extending in position spaced apart from the arms of the other fixture in a manner to divide the flow of flux of said magnet in a pair of uni-directional fields; an armature having the respective ends thereof in said fields; a plate for supporting said armature, said plate having a flexure area confined by a frame structure and having an opening in said flexure area through which said armature extends; and lugs on said fixtures to which said plate is adjustably secured in such a manner that said armature may be adjusted in position relative to said fixture arms by movement of said plate.
14. In a loud speaker, the combination of: a primary plate having a central opening and means for attachment of an amplifier, said primary plate having an inwardly turned lip formed around the edge thereof; a diaphragm resting against the rearward face of said primary plate; a secondary plate covering said diaphragm; and clips arranged around the edge of said secondary plate and engaging under said lip on said primary plate in a manner to force said secondary plate against said diaphragm.
15. In a loud speaker, the combination of: a primary plate having a central opening and means for attachment of an amplifier, said primary plate having an inwardly turned lip formed around the edge thereof; a diaphragm resting against the rearward

- face of said primary plate; a secondary plate covering said diaphragm; and clips arranged around the edge of said secondary plate and engaging under said lip on said primary plate in a manner to force said secondary plate against said diaphragm; a magnet; a yoke for holding said magnet against said secondary plate; means associated with said magnet for vibrating said diaphragm; a cupped cover member for said magnet, held in place by a screw threaded into said yoke.
16. In telephonic apparatus: a plate for supporting an armature, said plate having a flexure area confined by a frame structure.
17. In telephonic apparatus: a plate for supporting an armature, said plate having a flexure area confined by a frame structure consisting of a continuous channel depressed in said plate.
18. In telephonic apparatus: a plate for supporting an armature, said plate having a flexure area confined by a frame structure, and an elongated slot in said flexure area adapted to receive the armature.
19. In telephonic apparatus: a plate for supporting an armature, said plate having a flexure area confined by a frame structure consisting of a continuous channel depressed in said plate, and an elongated slot in said flexure area.
20. In telephonic apparatus: a plate for supporting an armature, said plate having a flexure area confined by a frame structure consisting of a continuous channel depressed in said plate, said plate having an elongated slot in said flexure area; and an armature in said slot transverse to said plate.
21. In telephonic apparatus: a plate for supporting an armature, said plate having a flexure area confined by a frame structure and having an elongated slot in said flexure area; and an armature in said slot transverse to said plate.
22. In telephonic apparatus: a plate for supporting an armature, said plate having a flexure area confined by a frame structure and having an elongated slot in said flexure area; an armature in said slot transverse to said plate; and a diaphragm responsive to the movements of said armature.
23. In telephonic apparatus: a plate for supporting an armature, said plate having a flexure area confined by a frame structure and having an elongated slot in said flexure area; an armature in said slot transverse to said plate; a diaphragm, and means connecting one end of said armature to said diaphragm.
24. In telephonic apparatus: a plate for supporting an armature, said plate having a flexure area confined by a frame structure and having an elongated slot in said flexure area; an armature in said slot transverse to said plate; a diaphragm; and means connecting one end of said armature to said diaphragm in said slot transverse to said plate; a diaphragm; and means connecting one end of said armature to said diaphragm, the other end of said armature being free.
25. In telephonic apparatus: a plate for supporting an armature, said plate having a flexure area confined by a frame structure and having an elongated slot in said flexure area; an armature in said slot transverse to said plate; a diaphragm responsive to the movements of said armature; a primary plate on one side of said diaphragm, said primary plate having an inwardly turned lip formed around the edge thereof; a secondary plate on the other side of said diaphragm from said primary plate; and clips arranged around the edge of said secondary plate and engaging under said lip on said primary plate in a manner to force said secondary plate against said diaphragm.
26. In telephonic apparatus: a plate for supporting an armature, said plate having a flexure area confined by a frame structure and having an elongated slot in said flexure area; an armature in said slot transverse to said plate; a diaphragm responsive to the movements of said armature; a primary plate on one side of said diaphragm, said primary plate having an inwardly turned lip formed around the edge thereof; a secondary plate on the other side of said diaphragm from said primary plate; and clips arranged around the edge of said secondary plate and engaging under said lip on said primary plate in a manner to force said secondary plate against said diaphragm.
27. In telephonic apparatus: a plate for supporting an armature, said plate having a flexure area confined by a frame structure and having an elongated slot in said flexure area; and an armature in said slot transverse to said plate, said armature being secured to the flexure area of said plate.
28. In a loud speaker, the combination of: a primary plate having a central opening, said primary plate having an inwardly turned lip formed around the edge thereof; a diaphragm resting against the rearward face of said primary plate; a secondary plate covering said diaphragm; and slips arranged around the edge of said secondary plate and engaging under said lip on said primary plate in a manner to force said secondary plate against said diaphragm.
29. In a loud speaker, the combination of: a primary plate having a central opening, said primary plate having an inwardly turned lip formed around the edge thereof; a diaphragm resting against the rearward face of said primary plate; a secondary plate covering said diaphragm; clips ar-

ranged around the edge of said secondary plate and engaging under said lip on said primary plate in a manner to force said secondary plate against said diaphragm; a magnet; a yoke for holding said magnet against said secondary plate; means associated with said magnet for vibrating said diaphragm; and a cupped cover member for said magnet, held in place by a screw threaded into said yoke.

10

In testimony whereof, I have hereunto set my hand at Los Angeles, California, this 13th day of November, 1923.

DELMAR A. WHITSON.

ranged around the edge of said secondary plate and engaging under said lip on said primary plate in a manner to force said secondary plate against said diaphragm; a magnet; a yoke for holding said magnet against said secondary plate; means associated with said magnet for vibrating said diaphragm; and a cupped cover member for said magnet, held in place by a screw threaded into said yoke. 10
In testimony whereof, I have hereunto set my hand at Los Angeles, California, this 13th day of November, 1923.

DELMAR A. WHITSON.

Certificate of Correction.

It is hereby certified that in Letters Patent No. 1,565,974, granted December 15, 1925, upon the application of Delmar A. Whitson, of Los Angeles, California, for an improvement in "Junior Loud Speakers," errors appear in the printed specification requiring correction as follows: Page 4, line 98, claim 6, for the word "plant" read *plate*; page 6, line 58, claim 23, after the word "diaphragm" strike out the comma and insert a semicolon, and line 117, claim 28, for the word "slips" read *clips*; and that the said Letters Patent should be read with these corrections therein that the same may conform to the record of the case in the Patent Office.

Signed and sealed this 19th day of January, A. D. 1926.
